UNITED STATES PATENT OFFICE

HERBERT G. IRWIN, OF AMARILLO, TEXAS

HAND FEED FOR ACETYLENE GENERATORS

Application filed August 18, 1927. Serial No. 213,731.

This invention relates to improvements in hand feeds for automatic acetylene generators of the carbide to water type whereby granular carbide may be fed by hand independent of the automatic carbide feed, as for an instance, in raising the initial operating pressure of gas in the generator after recharging the generator.

The object of my invention is to provide new and useful improvements in hand feeds for an acetylene generator.

A further object of my invention is to provide in a hand feed a means for wearing away lime deposit that may form on the carbide feed valve and upper side of the carbide hopper bottom about the feed valve when moisture finds its way to the feed valve.

A further object of my invention is to provide means for use in an acetylene generator in keeping the surface of the carbide feed valve and carbide hopper bottom about the feed valve in smooth condition.

A further object of my invention is to provide means for abrading lime deposit which forms on the feed valve and hopper bottom about the feed valve of an acetylene generator through ordinary use of the generator.

With these and other objects in view, my invention consists in the arrangement, combination and construction of the various parts of my improved device, as described in the specifications, claimed in the claims, and shown in the accompanying drawings, in which:

Figure 1 is a sectional view through a carbide hopper of an acetylene generator showing a hand feed constructed in accordance with my invention.

Figure 2 is a sectional view through a carbide hopper of an acetylene generator showing an alternate form in which my invention may be accomplished.

Figure 3 is a side view of the carbide hopper shown in Fig. 2 with side walls cut away showing the latter form of my invention at another angle.

Figure 4 is a longitudinal sectional view through a hand feed constructed in accordance with my invention.

Figure 5 is a longitudinal sectional view

through a hand feed showing another form in which my invention may be worked out.

Figure 6 is a longitudinal sectional view through a hand feed showing still another form in which my invention may be accomplished.

Referring to the accompanying drawings, the upper portion of the water chamber of an acetylene generator is indicated by numeral 1, the carbide hopper 2, the carbide hopper bottom 3, the automatic carbide feed control 4 and the carbide feed valve 5.

The form of the invention shown in Fig. 1 consists of a tubular guide 6, mounted inclined through the side wall of the carbide hopper extending in the direction of the carbide feed valve with the inner end a short distance from the valve.

The outer end of the guide is provided with a packing gland 7. Extending through this guide is a smooth round rod 8, which will be called a "cram-rod". The upper end of a handle bar 9, is pivoted to the outer end of the cram-rod.

A fulcrum link 10, has one end pivoted to a fixed post 11, and its other end pivotally connected with the handle bar a short distance below the upper end of the latter.

The cram rod has a longitudinal alternate motion in the guide upon working the handle bar, as by pulling the handle bar outward from the carbide hopper the cram-rod is moved inward of the hopper and then by pushing the handle bar back toward the carbide hopper the cram-rod is moved outward.

In outward position the inner end of the cram-rod is back some distance from the feed valve so as to be out of the way of carbide reaching the feed valve. In moving the cram-rod inward the inner end of the rod penetrates carbide above the valve and upon engaging the valve the latter is pushed open a distance sufficient to feed carbide in moderate quantity.

Such a hand feed may be used in an acetylene generator having an automatic feed and feed control, for raising by hand the initial operating pressure following each recharge with carbide and water. In so doing it may serve to remove lime deposit from the feed valve and upper side of the hopper bottom adjacent the feed

valve by working the handle bar fro and to in rapid succession so as to force the inner end of the cram-rod through the carbide above the valve a number of times without feeding much carbide. This causes the carbide 5 grains to grate upon the feed valve and hopper bottom which would wear away lime deposit. Thus it will be seen that such a device may be used in keeping the feed valve 10 in smooth condition as well as being used as a hand feed.

In Fig. 2 the cram-rod 8 is comparatively short and is mounted in a housing 12 adjacent the feed control housing 4A. The rod extends 15 on an incline through a spiral compression spring 13, and guide 6, to a point not far above the carbide feed valve 5. The upper end of the cram-rod is pivoted to one end of a short lever 14, which is mounted on a short rock shaft 15 disposed in suitable bearings 15J, in the upper end of the housing 12, as will be seen upon reference to Fig. 3. A handle shaft 17, extends through a packing gland and tube 18, in the side wall of the carbide hopper and connects with the rock shaft 15 through a universal joint 16. The housing 19 prevents carbide coming in contact with the inner movable parts of the shafts. In this instance the cram-rod is reciprocated longitudinally to clean the feed 30 valve and to open the feed valve by rocking the handle shaft 17 repeatedly. Upon turning the handle shaft about one quarter round clockwise the cram-rod is moved longitudinally toward the feed valve, the lower 35 end of the cram-rod being pushed through carbide above the feed valve, and upon reaching the feed valve the latter is pushed open a distance sufficient to feed carbide. The spring 13 tends to withdraw the cram-rod from the valve and carbide thus normally holding the cram-rod withdrawn when the hand shaft is released.

In Fig. 4 the handle-shaft 8 has a long hollow thimble 8B, over the lower end thereof for engaging carbide and the feed valve. The lower half of the guide 6 has a bore of such size in diameter as will telescopically receive the thimble. The thimble is mounted 50 in the guide to move longitudinally. And in order to prevent axial movement of the thimble in the guide when the handle-shaft is rotated and yet permit longitudinal movement of the thimble, a longitudinal groove 55 "X", is provided in the lower side thereof which is adapted to receive the inner end of a fixed screw 6E. The handle-shaft is mounted in the guide for rotary movement. And in order to prevent longitudinal movement 60 of the shaft in the guide the shaft is provided with a thrust annulus 8C, of such size in diameter as will fit rotatably in the upper extremity of the enlarged bore of the guide. A thrust bushing 6F, fixed below the 65 annulus confines the annulus to the upper end

of the bore thus preventing end play of the handle-shaft. The outer end of the guide 6 is provided with a packing gland 7, through which the handle-shaft extends. The outer end of the cram-rod is provided with a crank handle 8D, by which the handle-shaft may be rotated. By means of screwthreads on the lower half of the handle-shaft engaging screwthreads on the inner periphery of the thimble, the thimble is moved longitudinally 70 in the guide by turning the crank handle. This hand feed may be mounted in a carbide hopper in a manner similar to that shown in Fig. 1. Then upon turning the crank handle in one direction which will move the 80 thimble toward the feed valve some of the carbide above the feed valve will be pushed past the valve, and by turning the crank handle in the opposite direction the thimble will be moved away from the feed valve and carbide. It will be seen that by repeated turning of the crank handle several rounds in one direction and then several rounds in the opposite direction when the thimble is lowered into the carbide above the feed valve 90 gives the thimble a longitudinal alternate motion that will force carbide past the feed valve.

In Fig. 5 the cram-rod 8 is mounted in the guide 6 for both axial and longitudinal movement. The lower half of the cram-rod is provided with external screwthreads that engage internal screwthreads at 6H, in the guide. The upper outer end of the cram-rod terminates in a crank handle 8D by which the rod may be rotated to move the same longitudinally in the guide. It will be seen that by mounting this feed in a carbide hopper in a manner similar to that in Fig. 1 and by turning the crank handle in a clockwise direction the lower end of the cram-rod will be lowered to open the carbide feed valve, and then by turning the crank handle in the opposite direction the lower end of the cram-rod will be moved away from the feed valve. 100

In Fig. 6 the poke-rod 8 is a smooth round rod, mounted in the guide 6 for longitudinal movement. By pushing on the hand-hold 8Y, on the outer end of the poke-rod the lower end of the rod may be lowered to open the feed valve and by pulling outward on the hand-hold the lower end of the rod may be moved away from the feed valve. 110

It will be seen that by poking into carbide immediately above the feed valve or forcing carbide past the feed valve causes the carbide grains to grate upon the feed valve and hopper bottom about the feed valve. Such abrading has a cleaning effect on the feed valve and hopper bottom in that it wears away lime cake that forms at times on and about the feed valve which hinders the feeding of carbide. By having such a hand feeding means on an automatic acetylene generator to be worked every time the generator 120 125 130

is recharged or to be worked at will would not only keep down lime cake but would keep the surface of the feed valve and hopper bottom smooth, which goes to reduce resistance to the feeding of carbide in the automatic valve feed generator.

While I have shown and described several hand feeds constructed in accordance with my invention, it will be manifest to persons skilled in the art that many changes may be made in minor details of structure in adapting the feed to various generators, and slight changes in the mode of operation of same within the scope of the appended claims, without departing from the spirit of the invention; it is, therefore, to be understood that the invention is not to be limited to the details described and shown.

What I claim is:—

1. In a hand feed for an automatic acetylene generator having a carbide feed valve adapted to feed carbide from above the valve, a poke rod, one end of said rod directed toward said feed valve, a guide for holding said rod in the direction of said feed valve, a hand hold means for applying longitudinal alternate movement to said rod whereby the said end of the rod may be moved to abut against the feed valve and push the feed valve open for feeding carbide.

2. In a hand feed for an automatic acetylene generator having a carbide feed valve adapted to feed carbide from above the valve, a cram head in the vicinity of said feed valve, means for guiding said cram head in the direction of said feed valve, hand operated means for applying alternate movement to said cram head for cramming carbide down past the feed valve.

3. In a hand feed for an automatic acetylene generator having a carbide feed valve adapted to feed carbide from above the valve, a cram rod, one end of said rod directed toward said feed valve, a guide for holding said rod in the direction of said feed valve, spring means for normally holding said rod away from the valve, hand operated means for applying longitudinal alternate movement of said rod whereby said end of the rod may be moved toward said feed valve to cram carbide against the feed valve and to open the valve.

4. In a cleaner for the carbide feed valve of an automatic feed hopper of an acetylene generator, a cram rod, one end of said rod disposed in the vicinity of said feed valve and extending in the direction of the feed valve, a guide for keeping said rod in the direction of said feed valve, hand means for applying longitudinal alternate movement to said rod whereby the said end of the rod may be moved toward the feed valve through carbide present in the hopper above the feed valve to grate carbide against the feed valve and hopper bottom about the feed valve.

5. In combination, an acetylene generator

having a carbide feed hopper with a depressible carbide feed valve, a rod extending through the wall of the carbide hopper toward the carbide feed valve, guide means for said rod and including a packing gland, means for moving said rod in the guide to force the inner end of the rod through carbide above the feed valve and in contact with the feed valve to push the latter open, and means for withdrawing the rod from the feed valve.

6. In combination, an acetylene generator having an automatic carbide feed control including an elastic fluid pressure tank with means responsive to change of gas pressure in the generator having a vertical rod connection with a depressible carbide feed valve, an auxiliary comprising a second rod arranged obliquely of the first named rod and guided for longitudinal movement by hand for depressing the carbide feed valve to feed carbide into the generator.
